UNITED STATES PATENT OFFICE.

CHARLES J. CALLAHAN, OF ATTLEBORO, MASSACHUSETTS, ASSIGNOR TO C. H. ALLEN & COMPANY, OF ATTLEBORO, MASSACHUSETTS, A FIRM COMPOSED OF CHARLES H. ALLEN AND WILLIAM H. LAMB.

BRACELET-LINK.

1,082,473.

Specification of Letters Patent. Patented Dec. 23, 1913.

Application filed February 24, 1913. Serial No. 750,067.

To all whom it may concern:

Be it known that I, CHARLES J. CALLAHAN, a citizen of the United States, residing at Attleboro, in the county of Bristol and State of Massachusetts, have invented certain new and useful Improvements in Bracelet-Links, of which the following is a specification.

My invention relates to expansion bracelets of the slidable link type wherein middle links interengage in slidable relation with outer or guide links. In this type of bracelet the ends of the outer or guide links are composed of connecting posts riveted in position, or consist of downwardly directed ears having socket connections near their adjacent contacting ends, which have for that reason been required to be overlapped.

The objects of the present invention are essentially to avoid the resultant spreading of the bodies or outer guide links due to the unfastening of the posts or connected lugs and thereby to increase the strength of the bracelet band; and to effect this end in a construction which is inexpensive and easy to manufacture.

A further object is to increase the smoothness of the sliding action of the structure.

To the above ends essentially my invention consists in such parts and such combinations of parts as fall within the scope of the appended claim.

In the accompanying drawings which form a part of this specification: Figures 1 and 2 are plan and side elevations respectively of a bracelet constructed in accordance with my present invention, Fig. 3 a partial enlarged section of the same on line *v v* of Fig. 2, Fig. 4, a section of the same on line *w w* of Fig. 3, Figs. 5 and 6 and 7, sections on lines *x x*, *y y* and *z z* respectively of Fig. 3, Figs. 8 and 9, plan and end elevations respectively of one of the slide links, Fig. 10, a plan view of a blank from which the clenching member is formed, Figs. 11 and 12, plan and side elevations respectively of the original blanks from which the guide link is formed, and Fig. 13, a side elevation of the completed guide link.

Like reference characters indicate like parts throughout the views.

My bracelet comprises a plurality of interengaged inner or slide links A, and outer

or guide links B. In detail each inner link A consists of a flattened curved oblong loop having broad side walls *a*, and upon one end of the link oppositely disposed lateral posts *a*² located at the abutting ends *a*³ of the stock from which the link is originally cut and bent, best shown in Figs. 8 and 9. Each link member B is cut from a single blank and cupped up forming two curved oblong guide plates or shells *b* united by an intermediate retracted neck portion *b*¹ and having end ears or lugs *b*², the latter being provided with perforations *b*³. This blank B is next bent bringing the shells *b* into substantial parallelism, with the retracted portion forming an integral end post *b*¹, and the lugs *b*² are inwardly bent toward each other so that when the member B is complete the lugs *b*² have their adjacent edges in contact with each other and form substantially an end post, as clearly shown in Fig. 13.

Each inner link A slidably engages two adjacent guide links B, intermediate the two opposite shells *b* of each link B, and the projections *a*² extend within the sides of the shells which form guides for the links A. In each link A is a helical spring C having one end pressing against a post *b*¹, and its opposite end pressing against the end of the link A upon which the projection *a*² occurs so that the bracelet is held in retracted position thereby, as shown in Fig. 3. The relative positions of the described parts when the bracelet is partially expanded is shown in Fig. 4. It is vitally essential that the lugs *b*² be so firmly united as to avoid any possibility of their separation and the consequent distention of the shells *b* while the bracelet is in use, or is subjected to the great strain found in applying the bracelet over the hand on its way to the wrist. This end is effected by means of an auxiliary clenching member D, shown in detail in Fig. 10, which comprises a flat oblong rectangular body portion *d* with oppositely disposed end fingers *d*¹. The member D is composed of pliable metal. The body portion *d* of the member D is, as shown in Fig. 13, placed with its face abutting against the inner faces of the lugs *b*², and then the fingers *d*¹ are bent at right angles to the body *d* and passed through the openings *b*³ in the

lugs b^2 , and then downwardly bent against the outer faces of the lugs b^2 , and with their edges in contact with each other, so that the lugs are clamped or clenched together with their abutting edges in tight and immovable contact with each other.

What I claim is:—

A pair of bracelet links each formed with parallel shells, an end post integral with the shells at one end and lugs integral with the opposite ends of the shells and provided with perforations, a clenching member comprising a body resting against the sides of

said lugs and clamping fingers upon the body extending through the perforations 1¹ and bearing against the sides of the lugs opposite the body, and an inner link in one integral element embracing the post of one of said links and slidable between the shells.

In testimony whereof I have affixed my 2 signature in presence of two witnesses.

CHARLES J. CALLAHAN.
